ELECTRICAL CONNECTOR WITH
ADJUSTABLE COVER

Horatio H. Burtt, Hartsdale, William W. Koenig, Flushing, and Leon Gilbert, New York, N. Y., assignors, by mesne assignments, to Winchester Electronics, Incorporated, Glenbrook, Conn., a corporation of Connecticut

Application August 3, 1949, Serial No. 108,258

2 Claims. (Cl. 173—328)

1

This invention relates to electrical connectors and more particularly to electrical connectors of the panel mountable and separable part type.

It is an object of the present invention to provide in an electrical disconnect connector having parts sealed with respect to one another in an air tight manner and adapted to be sealed in a panel opening wherein the insulating parts containing male and female terminal elements can, upon the surrounding metal containing parts being released, be backed off from one another by the turning of a single coupling screw adapted to tighten the parts and draw them together and upon the turning of the screw in the opposite direction cause the backing off of one of the parts from the other, the other part remaining fixed upon the panel mounting and still sealed to prevent the leakage of air through the panel opening.

It is another object of the present invention to provide an electrical connector adapted for mounting upon a panel in an air tight manner with a seal being disposed between joined parts and which includes casing parts wherein a casing part receiving the lead-in wires which connect with the terminal contacts in one of the insulating parts can be adjusted upon a fixed casing part and turned at an angle with respect to the other casing part and such that the cable wires can lead from any one of a great number of angular directions from the connector, by the simple removal of a spring ring having specially formed axially extending projections which can be brought toward one another to release the ring and thereby to release the casing part upon the other casing part so that the adjustment can be effected and the engaging and retaining teeth on the one casing part entering different teeth on the other casing part which is fixed and wherein thereafter the adjustment has been made the spring ring can be easily put in place to hold the parts tightly coupled, the access to the spring ring being effected by the simple removal of a cover or plug part on the one casing part.

Other objects of the present invention are to provide an electrical connector of the separable and panel mountable type which is of simple construction, inexpensive to manufacture, easy to mount upon the panel, wherein the parts are sealed with respect to one another, has a minimum number of parts, compact, rugged, wherein the parts can be separated from one another and adjusted easily and quickly and efficient in operation.

For other objects and for a better understanding of the invention, reference may be had to the

2

following detailed description taken in connection with the accompanying drawing, in which

Fig. 1 is a longitudinal sectional view of the connector embodying the features of the present invention mounted upon a panel board, the view being taken generally on line 1—1 of Fig. 2 and looking in the direction of the arrows thereof.

Fig. 2 is an end elevational view of the connector.

Fig. 3 is an enlarged perspective and sectional view of certain of the parts of the connector and showing in particular the coupling and backing off screw arrangement.

Fig. 4 is a perspective view of the casing parts which can be angularly adjusted with respect to one another with portions broken away to show the peripheral teeth upon the parts which mesh with one another upon the angular adjustment of the one casing part being made with respect to the other casing part.

Fig. 5 is a transverse sectional view taken generally on line 5—5 of Fig. 1 and looking in the direction of the arrows thereof with portions being broken away to show the teeth upon the other casing part.

Fig. 6 is a perspective view of the spring ring which serves to retain the casing parts after the angular adjustment of the same has been effected, the ring having axially extending projections which can be easily grasped with pliers to contract the spring for the effecting of its removal from the groove of the one casing part and from its retaining position.

Referring now to the figures, 10 represents a panel on which the connector is mounted. This panel has an opening 11 for receiving an outer shell 12. This outer shell is provided with a shoulder 13 which contains a gasket 14 adapted to have sealing engagement with one face of the panel 10. This shell 12 is threaded at 15 to receive a nut 16 which enters a recess in the opposite face of the panel which secures firmly the shell 12 to the panel 10 and within the opening 11 thereof.

This shell 12 supports an insulating part 17 containing a plurality of circumferentially spaced female terminal contacts 18 and a central internally threaded ground terminal 19. The shell part 12 has internally extending flange 21 against which the insulating member 17 is brought and retained by an internally threaded retaining ring 22 connected to threads 23 of the shell part 12. A sealing grommet 24 is disposed between the insulating member 17 and the flange 21 of the outer shell 12.

Each female contact 18 is shouldered at 25 and held against a sealing ring 26 by a small spring retaining clip 27. The contact will have the usual projection 28 to which a cable wire can be soldered.

The central ground contact is shouldered, as indicated at 29, and this shoulder bears against a seal 30 in the insulating member 17. The terminal contact 19 is held in place in the insulating member 17 by a retaining nut 31. A portion 32 is provided on the terminal for receiving a cable wire. This terminal 19 is internally threaded, as indicated at 33, to receive a coupling screw 34 which has a flange 35 and adapted to bear against the end of the terminal 19 when all of the parts of the connector are in full coupled relationship, Figs. 1 and 3. The screw 34 forms a part of the male terminal contact assembly indicated generally at 36 and which can be removed as a unit from the panel 10 and from the connector parts fixed thereto. This assembly is to be presently described.

This male terminal assembly comprises generally a shell 37, a casing 38 angularly adjustable upon the shell 37, an insulating member 39 containing male contacts 41, a plug 42 and the coupling and backing off screw 34.

The shell or sleeve 37 is adapted to fit the shell 12. The shell 37 receives and tightly retains the insulating member 39. The shell 37 has an inwardly extending rib 43 which projects into a slot or groove 44 of the insulating member 39 to prevent the angular displacement of the insulating member relative to the shell 37. The shell 37 also has an external longitudinally extending groove 45 for receiving a longitudinally extending projection 46 of the outer shell 12 to properly locate the male contact assembly 36 within the shell 12 and to prevent the angular displacement of one shell with respect to the other. As the male contact assembly 36 enters the outer shell 12, the contact terminals 41 of the male assembly will be properly aligned with the female contacts 18 for connection therewith. The shell 37 has an outwardly extending flange 47 at its outer end and on the inner face of which is a series of teeth serrations 48. These teeth serrations receive complementary teeth serrations 49 on an inwardly extending flange 51 of the casing part 38. The casing part 38 can be angularly adjusted upon the inner shell 37 to any desired position to locate its sleeve projection 52 through which wire cables extend to any desired angle relative to the shell and relative to the fixed parts on the panel 10. Once the adjustment of the casing 38 has been made upon the sleeve 37, the teeth upon the parts will be retained in mesh with one another by spring retaining ring 53, Figs. 1 and 6. This ring has separable end portions 54 and 55 on each of which is an inwardly extending portion 56 with a longitudinal part 57. With a pair of pliers, the parts 57 can be grasped to contract the spring ring 53 and bring the end portions 54 and 55 together so that the ring can be located in groove 58 on the casing part 38 to hold the insulating member 39 as well as the casing part 38 and sleeve 37 in coupled relationship. A sealing ring 59 is disposed between the insulating member 39 and the flanged end of the sleeve 37. With the plug 42 removed from the casing part 38, access can be readily had to the ring 53 to remove the same and permit the parts to be adjusted to have the cable wires from the male contact terminals 41 and more particularly from

the end portions 61 thereof, extend at the proper angle from the connector.

The plug 42 has an inwardly extending sleeve projection 62 which contains the securing and backing off screw 34. Within the sleeve projection is a shoulder 63, Fig. 3, against which a shouldered portion of the screw 34 reacts to effect the backing off action of the male contact assembly 36. The shoulder on the screw is indicated at 64. The inner end of the sleeve projection 62 is sealed upon the insulating member 39 by seal 65. The insulating member 39 has a large opening 66 which receives the internally threaded central terminal and coupling member 19 secured to the insulating part 17.

The screw 34 has a nut 67, Fig. 3, for fixing it to the plug 42. In order to prevent the nut 67 from becoming detached, the end of the screw itself is upset, as indicated at 68, or provided with solder or such other suitable means as to make certain of the coupled relationship of the screw 34 with the plug 42. The screw 34 is journaled in the plug so that it can be turned therein to effect the coupling of the male contact assembly with the female contact assembly. Upon the reverse turning motion of the screw, the screw 34 with the parts assembled thereon and including the male contact 41 will be evenly backed off from the female contact assembly.

To effect the turning of the screw 34 there is provided a bail 71 and the ends thereof are made secure to the nut 67 by pins 72. These pins extend into openings 73 provided in the nut 67. Provided upon the bail 71 is a wide wing handle portion 74. The bail 71 with this handle portion can be pivoted upon the pin 72 so that the bail can lie in a recess 75 in the plug 42.

The plug 42 is flanged and can be turned on and off the casing part 38 when it is desired to have access to the interior of the casing part 38 to make the connection of cable wires to the portion 61 of the male contacts 41, or access to the ring 53 to remove the same and effect the relative adjustment of the casing part 38 upon the sleeve 37. A seal 76 is provided between the plug and the casing part 38.

On the sleeve projection 52 there may be disposed a cover sleeve 77 for the cable wires entering the casing part. The part 67 of the spring ring 53 may serve as a terminal for the connection of the ground wire since this ring is in contact with the casing part 38 to which the screw 34 which is coupled with the terminal 19 is connected by means of the plug 42.

It should now be apparent that there has been provided an electrical connector in which the female contact assembly can be readily fixed to the panel in sealing engagement therewith and wherein the parts thereof are in sealing engagement with one another so that leakage of pressure between the opposite sides of the panel will not result.

It should also be apparent that the male contact assembly has its parts sealed with respect to one another so that pressure leakage through it will not result. It should be further apparent that there has been provided in the male contact assembly means for effecting relative adjustment of the casing parts thereof and for retaining the same in the angularly adjusted position and that the male contact assembly is so constructed that its coupling member for the securement of the same to the female contact assembly serves to effect the disengagement of the assemblies by the reverse turning of the coupling member.

While various changes may be made in the detail construction, it shall be understood that such changes shall be within the spirit and scope of the present invention as defined by the appended claims.

What is claimed is:

1. A socket for an electrical connector comprised of separable contact assemblies, said socket comprising a sleeve, an insulating member fitted in said sleeve, contacts carried by the insulating member, said insulating member having a flange thereupon, said assembly sleeve having a flange engageable with the flange of the insulating member, said flange of the sleeve having on its forward face a series of teeth extending peripherally thereabout, an outer casing part having an inwardly extending flange with teeth on the inner face thereof engageable with the teeth of the flange of the other assembly sleeve whereby to hold the outer casing part upon the sleeve in angular adjustment thereupon, said outer casing part having a peripheral recess therewithin adjacent the flange of the insulating member and a spring locking ring adapted to be seated in the peripheral recess and engageable with the flange of the insulating member to hold the insulating member, the outer casing part and the other

assembly sleeve in locked engagement with one another and the outer casing part in locked engagement with the flange of the outer assembly sleeve.

5 2. The structure of claim 1 wherein the outer casing part and the spring ring are of conductive material, the spring ring having an inwardly extending projection therein serving for the contacting of the ring with a tool and adapted to receive a grounding wire terminal.
